Primary Examiner — Jennifer L Rempfer*Assistant Examiner* — Danielle Nichole Bowly(74) *Attorney, Agent, or Firm* — Nixon & Vanderhye(57) **CLAIM**

The ornamental design for a developing cartridge, as shown and described.

DESCRIPTION

FIG. 1 is a front perspective view of front, top and right side of a developing cartridge showing my new design;

FIG. 2 is a rear perspective view of rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are included for the purpose of illustrating portions of the developing cartridge that form no part of the claimed design.

1 Claim, 6 Drawing Sheets(56)
